INVENTOR

BY *Victor J. Evans*

ATTORNEY

O. Babia, Jr.

WITNESS:

UNITED STATES PATENT OFFICE.

HENRY ZINDEL, OF HAMMONTON, NEW JERSEY.

RING.

Application filed September 18, 1925. Serial No. 57,194.

This invention relates to finger rings and more particularly to a combined wedding ring and guard therefor, or combined wedding and engagement ring.

5 An object of the invention is to provide a ring structure which includes a guard or receiving ring formed of a single piece of precious metal with spaced ring members which may be decorated and carry precious 10 stones and which are connected at the inner portion of the band of the ring to provide a channel for receiving a part of the band ring and holding it against lateral or circumferential movement from between the 15 spaced sections of the guard ring.

Other objects of the invention will appear in the following detail description, and in the accompanying drawings wherein:

Figure 1 is a top view of the ring showing 20 one manner of decorating or constructing the end showing the band ring in place.

Figure 2 is a top view of the ring showing the band ring removed.

Figure 3 is a vertical section through the 25 ring with the band ring in place.

Figure 4 is an edge elevation of the ring with the band ring removed.

Figure 5 is a bottom view of the ring.

Referring more particularly to the drawings, the improved ring includes the guard or carrying section 1 which in turn comprises the sections 2 and 3, the tops of which may be ornamented in any desired manner and carry any number of precious stones of 30 any desired type. The bottoms of the bands of the sections 2 and 3 are connected by an integrally formed flat strip 4 which forms together with the bands 5 of the sections 2 and 3, a channel 6 in which the band ring 7 35 engages. The sections 2 and 3 may be spaced at proper distances apart so that the band ring 7 will fit snugly therebetween. If it is so desired, the band ring 7 may have its outer periphery ornamented in any 40 desired manner, or it may be perfectly plain depending upon the desires of the wearer. The channel 6 which is formed by the strip 5 extends some distance beyond the transverse center of the ring sufficient to prevent 45 circumferential movement of the band ring 7, relative to the sections 2 and 3, and the sections 2 and 3 prevent lateral movement of the band. It is to be noted that the pair of

ring sections of this improved finger ring are spaced co-axially, and that the bottoms 55 of said ring sections have the substantially long strip 4, of arcuate formation, on their circumferential outer surfaces, thereby connecting the two ring sections together. This substantially long flat strip 4 extends 60 the greater part of the bottom of the two ring sections and up along the sides. The two ring sections and the substantially long flat strip form the side walls and bottom of the U-shaped channel 6, so that the band 65 ring 7 may seat snugly between the two ring sections, to be supported by the bottom of the U-shaped channel, and held securely by the side walls, and against lateral displacement with the inner walls of the two ring 70 sections and the band being substantially flush.

The principal use for the improved ring structure heretofore described, is to provide a guard and ornamentation for wedding 75 rings to beautify the wedding ring and to add to its attractiveness. However, the sections 2 and 3 could be used as an engagement ring and receive the band wedding ring upon the performing of the wedding ceremony. 80

It is, of course, to be understood, that the invention may be constructed in various other manners and the parts associated in different relations, and therefore, I do not 85 desire to be limited in any manner, except as set forth in the claims hereunto appended.

What I claim is:

A finger ring comprising a pair of ring sections spaced co-axially, the bottom of said ring sections having on their circumferential outer surfaces a substantially long strip of arcuate formation connecting the two ring sections together and extending the greater part of the bottom of the two ring sections 95 and up along the sides, whereby a U-shaped channel is formed, the said strip forming the bottom and the two ring sections forming the side walls of the channel, a band ring fitting snugly and tightly between the two ring sections, supported at the bottom of the channel and held by the side walls thereof, the inner walls of the two ring sections and the band being substantially flush. 100

In testimony whereof I affix my signature.
HENRY ZINDEL.
